UNITED STATES PATENT OFFICE.

MOSES E. JOHNSON, OF PITTSBURGH, PENNSYLVANIA.

FENCE-POST.

1,070,261.

Specification of Letters Patent. Patented Aug. 12, 1913.

Application filed November 25, 1912. Serial No. 733,485.

To all whom it may concern:

Be it known that I, MOSES E. JOHNSON, a citizen of the United States, residing at Pittsburgh, in the county of Allegheny and State of Pennsylvania, have invented certain new and useful Improvements in Fence-Posts, of which the following is a specification, reference being had therein to the accompanying drawing.

10 This invention relates to a fence post of sheet metal construction, one object of the present invention being to provide a comparatively simple, durable and inexpensive fence post made of a single piece of sheet metal shaped into tubular form and provided with integrally formed fence wire attaching means.

20 Another object of the invention is the provision of a sheet metal post of the clip-less type but provided with a novel arrangement of tongues, lugs or projections and depressions for holding the fence wires on the post against upward and downward strains, as well as longitudinal strains.

25 With these objects in view and others, as will appear as the description proceeds, the invention comprises the various novel features of construction and arrangement of parts which will be more fully described 30 hereinafter and set forth with particularity in the claims appended hereto.

In the accompanying drawings which illustrate certain embodiments of the invention, Figure 1 is a perspective view of a 35 portion of the post showing the wire retaining lugs in outstanding or open position. Fig. 2 is a transverse section on line 8—8, Fig. 3. Fig. 3 is a vertical section through a portion of the post showing one 40 set of lugs open and another set of lugs closed over a fence wire. Fig. 4 is a perspective view of a portion of the post showing a modified arrangement of lugs. Figs. 5 and 6 are front and perspective views, 45 respectively, of a portion of the post showing the modified lugs closed and retaining a fence wire. Fig. 7 is a fragmentary view of a post showing another arrangement of wire-holding lugs.

50 Similar reference characters are employed to designate corresponding parts throughout the views.

Referring to the drawings, the blank from which the post is made consists of sheet 55 metal of suitable gage, and is of such proportions that the completed post will have

a slight taper or convergence upwardly throughout the major portion of its length, say, to a foot from the lower end, and from this point the lower or base portion will taper in a reverse direction as shown in Fig. 7. The upper or major portion of the post may be, if desired, non-tapering.

The blank is formed in any suitable manner so that the lateral edges of the blank 60 meet and form a seam or joint 3, Fig. 1, extending throughout the length of the post, and in transverse cross-section the post is circular at every point. In imparting this curvature to the blank, the metal, of course, 65 must be drawn in the region of the widest portion of the blank, so that the downwardly-tapering base portion 4 of the post will be coaxial with the upper portion 5. Obviously, the post will be hollow throughout its length and the bottom and top are 70 open.

The fence wires are fastened to the post without the use of clips or any applied fasteners, as integral lugs are employed for this 75 purpose. For each wire, a pair of lugs 9 and 10 are stamped out of the metal of which the post is made, one lug extending downwardly and the other lug extending upwardly, so that the wire will be embraced 80 by two lugs, thereby effectively holding the wire against both an upward and downward strain, and at the sides of the lugs are deep 85 depressions 11 that form seats for the wire to coöperate with the lugs for resisting upward and downward strain and also for forming shoulders against which a bight or kink in the wire bears to prevent longitudinal 90 movement of the wire, said bight or kink being formed by the forcing of the lugs or 95 tongues 9 or 10 into wire-embracing position, as will be clearly shown in Fig. 2. In Figs. 1, 2 and 3, the lugs 9 and 10 are rectangular in shape and are formed by the 100 making of two parallel slits 12 and a transverse slit 13 in the metal of which the post is made. These slits may be formed while the blank is flat, or after the blank is partially curved, the forming of the slits being a preliminary part of the operation of forcing the lugs 9 and 10 to outstanding or open 105 position, and at the same time the lugs are formed, the depressions 11 may be made.

When the lugs are open, as shown in Fig. 1, a wire 15 is passed in between them through 110 the gap 14, and after the wire is engaged in the seats or depressions 11, the lugs 9 and

10 are bent backwardly over the wire, as shown in Figs. 2 and 3. In forcing the lugs or tongues 9 and 10 to closed position or into engagement with the wire 15, a bight or 5 kink 16 is imparted to the wire, which, by engagement with the seats or depressions 11 and the lugs 9 and 10, prevents longitudinal movement of the wire, as will be evident from Figs. 2 and 3, which also show the lugs 10 9 and 10 approximately flush with the external surface of the post.

Instead of having the lugs separated on a transverse line, they may be separated obliquely to form lugs 9^a and 10^a, as shown 15 in Figs. 4 and 6. In this case, the lugs, when closed down will embrace more of the wire, the apexes 12^a being bent inwardly to engage the wire.

Another arrangement of lugs is shown in 20 Fig. 7, wherein the lugs 17 and 17^a are formed between spaced holes 18 and 19 punched in the metal of the post and a slit 20 extending from the top of one hole to the bottom of the other hole in approximately 25 tangential relation, and depressions or seats 21 are formed laterally of each hole or at the outside thereof. Before the wire is applied, the lugs 17 and 17^a are outstanding, as shown at *b*, Fig. 7, so that the wire can be 30 placed in between the lugs and engaged with the seats 21. The lugs 16 and 17 are then bent over the wire to closed position, as shown at *c*, Fig. 7. It will thus be seen that in the various arrangements of lugs, the wire 35 is retained in place with twice the holding power of those fence posts having only single lugs for each wire, and the depressions or seats at the lateral edges of the lugs are also important in assisting in holding the 40 wire against displacement under downward or upward strains. Furthermore, the depressions or seats coöperate with the lugs to form the bight or kink in the wire where it is engaged with the post, so that longitudinal 45 slipping is prevented.

From the foregoing description, taken in connection with the accompanying drawings, the advantages of the construction and of the method of operation will be readily apparent to those skilled in the art to which 50 the invention appertains, and while I have described the principle of operation of the invention, together with the device which I now consider to be the best embodiment thereof, I desire to have it understood that 55 the device shown is merely illustrative, and that such changes may be made when desired as are within the scope of the claims appended hereto.

Having thus described the invention, what 60 I claim as new, is:—

1. A tubular fence post having a pair of wire retaining bendable lugs, one lug extending downwardly and the other lug upwardly and both arranged in the same vertical plane, depressions being formed in the curved wall of the post and at the sides of the lugs forming wire engaging seats, both of said lugs engaging the wire to hold the same in its seat. 65

2. The combination of a tubular fence post, with a wire, said post having spaced depressions forming wire engaging seats, and lugs extending respectively downwardly and upwardly over the wire and located in 70 vertical alinement between the said depressions, the wire being formed into a bight or kink under the lugs by the forcing of the latter into wire holding position, said bight engaging with the edges of the seats and 75 lugs for preventing longitudinal slipping of the wire, and the said seats and lugs coöperating to resist upward and downward strain on the wire.

In testimony whereof I affix my signature 80 in presence of two witnesses.

MOSES E. JOHNSON.

Witnesses:
